Eugene C. Gott, Jr.
Attorney.

UNITED STATES PATENT OFFICE.

LENORE BOATRIGHT, OF SAUSALITO, CALIFORNIA.

DESIGN FOR A JAR OR SIMILAR CONTAINER.

Application filed December 19, 1927. Serial No. 24,543. Term of patent 3½ years.

To all whom it may concern:

Be it known that I, LENORE BOATRIGHT, citizen of the United States, residing at Sausalito, in the county of Marin, State of California, have invented a new, original, and ornamental Design for a Jar or Similar Container, of which the following is a specification, reference being had to the accompanying drawing, forming a part thereof.

I claim:

The ornamental design for a jar or similar container as shown.

LENORE BOATRIGHT.
